CASPAR METTLER, OF NEW HAVEN, CONNECTICUT, ASSIGNEE TO NASHUA CARD,
GUMMED & COATED PAPER COMPANY, OF NASHUA, NEW HAMPSHIRE, A CORPO-
RATION OF MASSACHUSETTS.

DRINKING-CUP.

1,127,793.

Specification of Letters Patent.

Patented Feb. 9, 1915.

Application filed January 20, 1912. Serial No. 672,418.

To all whom it may concern:

Be it known that I, CASPAR METTLER, a citizen of the United States, and resident of New Haven, in the county of New Haven 5 and State of Connecticut, have invented a new and useful Improvement in Holders for Collapsible Drinking-Cups, of which the following is a specification.

The object of my invention is to provide a 10 holder for use in combination with collapsible tubular drinking cups having unsealed bottoms, said holder serving as a means for temporarily sealing the bottoms of the cup members and supporting the sides of the cup 15 members when filled.

A further object is to provide a holder of the above character in which the cup members may be readily inserted and as readily removed.

20 A practical embodiment of my invention is represented in the accompanying drawings, in which—

Figure 1 is a top plan view of the holder showing a collapsible tubular drinking cup member of the character above described inserted into position therein, Fig. 2 is a side view of the same, Fig. 3 is a side view taken at right angles to Fig. 2, and Fig. 4 is a vertical central section through the holder 25 and cup member with the jaws closed in full lines and open in dotted lines.

The collapsible tubular drinking cup member is denoted by 1 and is of the type which forms the subject matter of my co-pending application filed of even date herewith, its serial number being 672,419. The bottom of this drinking cup member is unsealed and it therefore must be used in connection with means for temporarily sealing 35 said bottom to permit the cup member to act as a container for liquid.

The holder comprises a base 2 and jaws 3 and 4 uprising therefrom. In the present instance, the jaw 4 is shown as a fixed jaw 45 preferably formed integral with the base 2 and the jaw 3 is shown as a movable jaw hinged at 5 to the base 2. These jaws are normally open and a stop may be provided for limiting the outward movement of the movable jaw 3, which stop is herein shown as a lug 6 uprising from the base 2. These jaws have laterally extended coating surfaces 7 and 8 at their inner ends arranged

when closed to pinch the walls of the cup member together at its bottom to seal the 55 same for permitting the cup member to hold a liquid. These jaws may be provided with means for supporting the sides of the cup members when filled, as, for instance, laterally extended arms 9, 10, and 11, 12, which 60 form supports for the sides of the cup member when filled with a liquid. These arms are preferably curved so as to follow the contour of the drinking cup member when opened by the liquid therein. Means are 65 provided at the bases of the jaws for registering the bottom of the cup member between the sealing surfaces 7, 8, which means are shown herein as guards 13, 14, formed by lateral extensions of the base of the fixed 70 jaw 4.

In operation, the collapsible tubular drinking cup member with its unsealed bottom is inserted into the holder with its bottom between the sealing surfaces 7, 8, of the 75 jaws, the guards 13, 14, serving to register the cup member properly. The movable jaw 3 is then swung inwardly toward the fixed jaw 4, thus causing the walls of the cup member to be pinched together at its 80 bottom to seal the same. As the liquid is then poured into the cup member, the jaws will also serve to support the sides of the cup member in a proper position for drinking. As soon as the person using the cup member 85 is through with the same, the cup member may be readily ejected from the holder by simply permitting the movable jaw 3 to swing outwardly to its normal open position. The holder is then ready for the next succeeding cup member.

It is evident that slight changes might be resorted to in the form, construction and arrangement of the several parts without departing from the spirit and scope of my invention: hence I do not wish to limit myself 95 strictly to the structure herein set forth, but

What I claim is:—

1. A holder for a paper vessel having a normally unsealed bottom, said holder comprising two diverging upright members movable toward and from each other and having their upper portions formed to substantially inclose the vessel, the lower portions of said members being relatively positioned to pinch the lower portion of the vessel.

- sel when the upper portions of the members are moved to relative positions to steady the vessel for drinking purposes.
2. A holder for a paper vessel comprising 5 two members movable toward and from each other, the lower portions of the members being straight and relatively positioned to pinch the lower portion of the vessel, the upper portions of the members diverging 10 to support the sides of the vessel.
3. A holder for a paper vessel, comprising two diverging members movable toward and from each other, said members having pinching portions and vessel-embracing portions movable with the pinching portions.
4. A holder for a paper vessel comprising 15 two members movable toward and from each other, the lower portions of the members being straight and relatively positioned to pinch the lower portion of the vessel, the upper portions of the members diverging to support the sides of the vessel, one of said members having a rigid base.

5. A holder for a paper vessel, comprising two pivotally connected pinching members 25 having diverging extensions to steady the sides of the vessel for drinking purposes, said extensions presenting portions to be grasped to hold the vessel with its bottom pinched.

6. A holder for a paper vessel, comprising 30 two pivotally connected pinching members having diverging extensions the upper portions of which are laterally curved to steady the sides of the vessel for drinking purposes, said extensions presenting portions to be grasped to hold the vessel with its bottom pinched.

In testimony, that I claim the foregoing 40 as my invention, I have signed my name in presence of two witnesses, this nineteenth day of January 1912.

CASPAR METTLER.
